DRAFT BRACE

Samuel B. Richardson, Declo, Idaho

Application May 16, 1936, Serial No. 80,150

3 Claims. (Cl. 56—218)

This invention is a draft brace and the object of the invention is to provide a brace especially adapted for use on mowers for bracing the draft tongue with respect to the axle of the mowing machine.

The invention together with its objects and advantages will be best understood from a study of the following description taken in connection with the accompanying drawing wherein:

- 10 Figure 1 is a plan view illustrating the application of the brace, and
Figure 2 is a side elevational view of the brace.
Referring to the drawing by reference numerals it will be seen that in the preferred embodiment thereof the brace indicated by the reference numeral 5 is formed from a tubular rod of suitable length one end of which is flat and apertured as at 6 for attachment to the draft tongue 7 of a mowing machine indicated generally as 8 at one side of the draft tongue through the medium of bolts or the like 9 and at a point approximately one foot in advance of the double tree or evener 10 as shown in Figure 1.
At its respective opposite end the brace rod 5 is bifurcated to form extensions or fingers 7 that are bent into a plane offset from the plane of the rod 5 and form a fork adapted to straddle the axle 12 of the machine as shown in Figure 1. A two part clamp or the like 13 is engageable with the extensions 11 in a manner suggested in Figure 1 for drawing these extensions tight about the axle 12 to prevent lateral movement of the end of the brace bar associated with the axle lengthwise along the axle.
35 A brace block 14 extends laterally from the tongue 7 and is secured to the tongue by straps or the like 15. At its free end block 14 has a hole therethrough through which extends the brace rod 5 as shown.
40 Thus it will be seen that a bar applied in the manner shown will serve to admirably brace the draft tongue of a mower or similar machine.

It will also be appreciated that a brace bar providing the features of the present invention can be cheaply and economically made and can be attached in position with a minimum amount of effort and without requiring a great deal of skill.

It is thought that the invention together with its advantages will be understood without a more detailed description.

Having thus described the invention what is claimed as new is:

1. In combination with the draft tongue and front axle of a mower or like machine, a draft brace comprising a single length of rod provided at one end for lateral engagement with the draft tongue and adapted at said end to be positively secured to the tongue, said draft brace at its respective opposite end being forked and having said forked end straddling said axle.
2. In combination with the draft tongue and front axle of a mower or like machine, a draft brace comprising a single length of rod provided at one end for lateral engagement with the draft tongue and adapted at said end to be positively secured to the tongue, said draft brace at its respective opposite end being forked and having said forked end straddling said axle, and a clamp engaging the forked end of the brace rod for securing said end in binding engagement with the axle.
3. As a new article of manufacture a brace rod for a draft tongue of mowers and like machines comprising a single length of tubular rod having one end flat and apertured and its respective opposite end split with the portions formed by the split extended longitudinally and in parallelism to provide a fork adapted to straddle the axle of the mower and means connecting the forked ends to each other to secure the axle in the fork.

SAMUEL B. RICHARDSON.
